AERIAL HAND GRENADE.
APPLICATION FILED JUNE 17, 1916.

Patented Aug. 14, 1917.

2 SHEETS—SHEET 2.

UNITED STATES PATENT OFFICE.

LESTER P. BARLOW, OF PHILADELPHIA, PENNSYLVANIA, ASSIGNOR TO MARLIN ARMS CORPORATION, OF NEW YORK, N. Y., A CORPORATION OF NEW YORK.

AERIAL HAND-GRENADE.

1,237,012.

Specification of Letters Patent. Patented Aug. 14, 1917.

Application filed June 17, 1916. Serial No. 104,209.

To all whom it may concern:

Be it known that I, LESTER P. BARLOW, a citizen of the United States, residing in the city and county of Philadelphia and State of Pennsylvania, have invented a new and useful 'Aerial Hand-Grenade, of which the following is a specification.

My invention relates in general to aerial warfare and in particular to explosive bombs of the character of those which are adapted to be dropped from aeroplanes or other flying machines.

In this class of grenades, two requirements have to be met; first, the grenade as an entirety must be adapted to drop perpendicularly or vertically so as to strike the earth or other object to be encountered at a right angle to the assumedly horizontal plane of contact; and, second, provision must be made for the explosion of the bomb above the object struck and not, as particularly in the case of striking the earth, within the object struck, with the necessary result of a confined explosion. When, however, the object struck is the earth, it is a further advantage, if not a necessary requirement, that the bomb proper after embedding itself for a given distance should extrude a further given distance and should not penetrate too deeply.

These objects I accomplish by a grenade of the general type of construction which is represented in the accompanying drawings and hereinafter described, in which provision is made for stabilizing the grenade in its vertical descent, for preventing its too deep embedment, and, further, for expelling the bomb outwardly and upwardly from its carrying gun-shell before its explosion.

To the foregoing general ends, my invention comprehends a bomb-carrying gun of such organization that when it encounters the object to be struck, it first embeds itself in such object to a given distance and maintains a fixed vertical position therein,—that then, and in so doing, it explodes by concussion or gun contact so to speak, a primary delay cap,—which then explodes a primary delay charge or fuse,—which then explodes an expelling charge which expels the bomb proper and with it both fires and also expels a secondary delay charge or fuse, which in turn and finally explodes the bomb after its expulsion from the gun.

The timing of the successive explosions of

these successively disposed and successively exploded charges is accurately calculated, and is, as stated, such that the ultimate explosion or that of the bomb or torpedo does not take place until after the bomb has been completely expelled from the bomb-carrying gun-proper at the rear or that end which is always open as opposed to the forward or breech end or that which is closed by the breech-mechanism and the firing mechanism.

As a result of the general organization of my grenade, it results that, when dropped, it not only falls breech downward so as to penetrate the earth or object struck,—but also that the bomb leaves the gun while the latter is presumably in an upright position,—and that the explosion of the bomb takes place at a given distance above the gun, and not until it is wholly free from the gun and the latter has come to a standstill.

By bringing the gun to a standstill before the ejection of the bomb, less downward motion has to be considered, and the expulsion of the bomb is accomplished when the shell has been caused to penetrate but a short distance so that its tail or open-end is not embedded and partly inclosed within the earth, but left open to permit of and guide the outward throw of the bomb.

A good construction but not necessarily the only one to accomplish all of these desired objects is the following.

Referring to the drawings:

Fig. 1 represents in side elevation, a grenade embodying a preferred form of my invention.

Fig. 2 represents an enlarged, central, vertical, sectional elevation through the grenade of Fig. 1.

Fig. 3 represents a fragmentary enlarged detail of the lower portion of the gun-shell and torpedo, particularly illustrating the breech block and its adjuncts and a part of the head of the penetrating nose. In all of these three views, the cotter pin is in place.

Fig. 4 represents a top plan view of the grenade as represented in Fig. 1.

Fig. 5 represents a sectional top plan through the grenade of Fig. 2 on the plane of the dotted line 5—5 of said Fig. 2.

Fig. 6 represents a similar sectional top plan view on the line 6—6 of Fig. 2.

Fig. 7 represents a view similar to that of Fig. 2, indicating, however, the position of the parts when the grenade has been

dropped and plunged into the ground and when the bomb-expelling charge has shot the bomb almost clear of the gun-shell.

Fig. 8 represents a perspective of the flanged collar of the bomb removed from the bomb and viewed from on top.

Fig. 9 represents a similar view of the collar viewed from underneath.

Fig. 10 represents a perspective view of one of the delay fuses.

Fig. 11 represents a perspective, viewed from above, of the primary charge cap removed from the breech block.

Fig. 12 represents a similar view of the same, viewed from the bottom.

Similar numerals of reference indicate corresponding parts.

Referring to the drawings:—

1 designates a shell or casing which I term the gun-shell, within which is contained the bomb or torpedo 2. This gun-shell is a cylinder of sheet metal, at its upper or outer end formed with stabilizing wings or blades which I term the stabilizers 3, and which are preferably formed by stamping out longitudinal segmental sections of the shell so that they protrude diametrically outward from its axis, as shown particularly in Fig. 4. They may, of course, be separately attached.

At its lower or striking end, the shell is slotted or cut longitudinally so as to form what I term spreading flanges 4, any desired plurality of which may be formed by slots 5 of desired breadth stamped out of the substance of the walls of the shell. These flanges when spread by contact with the earth serve both to prevent too deep penetration and to anchor the shell.

Within the lower or outward end of the shell is inserted a gun-breech-mechanism, or breech-block, 6, preferably of the form indicated in the enlarged view of Fig. 3.

This breech block fills the interior of the lower end-portion of the shell, is cylindric and conveniently secured permanently within the shell preferably but not necessarily by being formed with circumferential external grooves 7 into which the walls of the shell are forced or crimped by being formed into the circumferential internal beads 8, which fill within the grooves of the breech.

The upper portion of the breech is hollowed out to form an enlarged chamber 55 which I term the explosive chamber 9, within which is contained the bomb-expelling charge of any preferred explosive 10.

The lower portion of the breech is hollowed out to form a nose-chamber 11, preferably cylindric, within which is entered and located the head portion or head-block 12 of the penetrating nose 13 which latter is of conical form and preferably protrudes from the lower open end of the gun shell,—being in part, or as to its conical or tapering area,

preferably encompassed by the spreading flanges 4, and in part, or as to its cylindric basal area 14, preferably fitted within what I call a base-chamber 15 of the breech block. The head-block 12 or upper portion of the nose is upon its upper inner surface formed or provided with a firing pin 16 to strike and fire the explosive cap 17.

The nose-piece 13, it will be observed, acts in conjunction with flanges 4 to stop the descent of the shell through the earth, since the nose-piece forces the earth between the same and the flanges, outwardly against the flanges, to spread the latter apart.

From the foregoing construction, it results that the nose piece as an entirety is so related to the nose chamber 11 and the base chamber 15 of the breech block within which it snugly fits, as to be capable of a longitudinal movement with respect to said block and of course with respect to the gun-shell, and that the device constitutes a firing mechanism.

The nose is normally retained in the position represented in Figs. 1, 2, 3 and 6, by a cotter pin 18, which is entered within and through a diametrically located pin tube 19 of copper or other relatively soft sheet metal, which passes through a cylindric bore 20 drilled diametrically through the breech block and a correspondent bore 21 drilled through the head block 12 of the nose 13, so that in the assembling of the parts, the two bores register and permit of the fixed introduction of the pin tube through them both, so as to normally retain the nose in the position represented in Figs. 1, 2 and 3, the cotter pin which, as stated, is introduced through the pin tube 19, assuring the retention of the nose.

Assume the cotter pin first withdrawn from its tube when the grenade is dropped, and the nose still remaining in the position represented in Fig. 1,—it is obvious that under these conditions the upward and inward driving of the nose such as will be occasioned when it strikes the ground or other object to be encountered, will cause the soft pin tube to be cut through and so permit of the driving up of the nose, as shown in Fig. 7, until its firing pin 16 encounters the fuse cap 17 and explodes it. This device is, therefore, a breakable connection between the breech-mechanism and the firing-mechanism.

Below the explosive chamber 9, and axial of and within the breech, is formed what I term the primary delay-chamber 22, preferably cylindric and internally threaded, within which is secured what I term a primary charge-cup 23, which is of pill-box form and perforated through its bottom by the perforations 24, as will be understood from Figs. 11 and 12.

Within this primary charge-cup is in-

serted a primary delay-fuse 25 (Fig. 10) of an explosive mixture the period of explosion of which is calculable and relatively slow, and which is centrally perforated at 5 26 to register with a bore 27 axially formed in the breech and opening into a fuse cap-chamber 28 in the breech within which is inserted and contained the explosive cap 17.

It will be understood that when the fuse 10 cap 17 is exploded by the stroke of the firing pin 16, its charge, passing through the bore 27 into the central perforation 26 of the primary delay fuse 25, will occasion the explosion of such fuse upwardly through the 15 perforations 24 in the primary charge cup 23 and into the bomb-expelling charge 10 within the explosion chamber 9, so as to explode said charge.

The bomb or torpedo 2, a hollow cylindrical shell or casing, is formed with an internal bomb-chamber 29 within which is contained the bomb-bursting-explosive 30. The bomb-chamber 29 is closed at its upper or inner end by the closure 31, and is open at 20 its lower end and formed with a circumferential shoulder 32, Fig. 7, and with a tubular externally-threaded downward extension 33, which is fitted to be threaded within a threaded upper opening 34 of the breech 25 block, so that in the introduction of the torpedo within the gun, the torpedo is screwed 30 and so secured to the breech block.

The threads which form the threaded connection between the torpedo and the breech 35 block are, however, of slight depth, so that in the explosion of the bomb expelling charge 10, they may be readily stripped or drawn apart to set the bomb free. Other forms of readily detachable connection may, 40 however, be resorted to.

Within the lower open end of the bomb is introduced a secondary delay fuse 35, the explosion of which occurs after the explosion of the bomb-expelling charge 10, 45 and occasions the explosion of the bursting explosive charge 30 within the bomb.

This secondary delay fuse is conveniently a reverse counterpart of the primary delay fuse and is applied and formed as follows:

36 is a retaining flanged collar shown in both Figs. 8 and 9, also of pill-box shape and formed with a central firing hole 37 through its bottom.

55 This cap-like collar 36 is externally threaded and is preferably adapted to be screwed into the lower threaded open end of the bomb, Fig. 7, so that it fills in the open bottom of the bomb chamber 29 and 60 confines the bursting explosive 30 between it and the top closure 31 of the bomb.

Within this retaining collar 36 is introduced, preferably by being threaded in, a secondary charge cup 38 generally counter- 65 part of the primary charge cup 23 but

adapted to be reversely disposed. This cup is also formed with perforations 39 through its bottom, and is adapted to contain a secondary delay fuse 35, which is generally similar in composition and period required 70 for explosion, to the primary delay fuse 25 already described.

So far as it has not already been described, the operation of my grenade is the 75 following:

The elements already described being assembled as shown in Figs. 1, 2 and 3—it will be understood that there are contained within the grenade as an entirety when it is charged and ready for operation, five 80 successive explosive charges:—first, that of the fuse of the explosive cap 17 which is set off by the stroke of the firing pin 16 when the grenade has encountered the ground or other object to be struck and its nose has 85 been not only driven into the ground or object but also forced inwardly and upwardly to touch off said explosive cap;—second, that what I have called the primary delay fuse 25, which is set off by the explosion of 90 the cap fuse and in turn operates upon the bomb-expelling charge to set it off;—third, the bomb-expelling charge 9 itself, which when set off, sets off the secondary delay fuse 35;—fourth, the secondary delay fuse, 95 so, as explained, touched off by the bomb-expelling charge and which in turn sets off the charge of bursting explosive 30 within the bomb;—and, fifth, the charge of bursting explosive within the bomb.

100 It is of the essence of my invention that the timing or order of discharge of these five explosive charges should be both definite and in predetermined successive order and this is insured by the selected character of 105 the explosives themselves.

Thus, the discharge of the explosive cap cannot take place until the grenade as an 110 entirety has embedded itself to a certain distance within the ground or object to be struck, and so has driven the penetrating nose backward into the shell.

The driving of the nose into the ground also and at the same time occasions the 115 expansion of the spreading flanges of the gun-shell by the forcing out action of the earth or other substance of the object struck between the conical surfaces of the nose and the internal surface of the flanges, so as to occasion the spreading out of the flanges in 120 the manner typified in Fig. 7, and to further prevent the too deep sinking in of the grenade and occasion the retention of its lower portion within the ground or other object struck, as clearly shown in said figure. Thus, 125 further, the explosion of the primary delay fuse which takes place as the result of the explosion of the fuse cap, is a delayed charge which for a small fraction of a second delays 130 the explosion of the bomb-expelling charge

10, the explosion of which latter is sufficient to light but not to explode the secondary delay fuse which later on occasions the explosion of the bomb when completely ejected 5 from out the upper end of the gun shell.

Thus, further, the explosion of the secondary delay fuse or charge is a delayed explosion taking place within a very short period, calculated, however, not to take place, 10 and so occasion the explosion of the bursting explosive and of the bomb, until after the bomb has cleared the gun shell some predetermined distance, say, for instance, some eight or ten feet.

15 In speaking of delayed explosions, it is to be understood that in the art of compounding and making various explosive mixtures, it is possible to make them of such character and composition, that the time within 20 which,—after their first touching-off or firing, so to speak,—they will explode, is accurately calculable to within fractions as small, for instance, as one-fifth of a second,—and that I, therefore, simply utilize such selected 25 mixtures as may be necessary for organizing my grenade in a way such that when it strikes the ground, the consecutively disposed mixtures will successively explode in the order of their successive disposition within the shell.

30 Thus, when the gun shell has plunged a given distance into the ground and its spreading flanges have been spread as shown in Fig. 7 so as to retain it in that position; and when, also, the penetrating nose has 35 been driven inward and upward, the first explosion will be that of the fuse cap 17,—the second, that of the primary delay charge 25,—the third, that of the bomb-expelling charge 10, which will occasion the explosion 40 of the bomb,—the fourth, that of the secondary delay charge 35 which will not take place until after the bomb has been expelled a predetermined distance out of the gun shell,—and, fifth and last, that of the bursting charge 30 occasioned by the explosion of the secondary delay charge and resulting 45 in the explosion of the bomb wholly above and beyond the gun shell and not within the ground where its explosion would be less 50 effectual.

Having thus described my invention, what I claim as new and desire to secure by Letters Patent, is:—

1. In an aerial grenade, the combination 55 of an outer shell, having spreading flanges at its forward end, and a nose-piece between said flanges, tapering upwardly and outwardly from its lower end, to force earth outwardly against said flanges to spread the 60 same when the grenade strikes the ground, the grenade being constructed to fall forward end first.

2. In an aerial grenade, the combination 65 of an outer tubular shell, open and provided with spreading flanges at its forward end, a

recessed breech-block secured within said shell, a nose-piece mounted in the forward end of said breech-block and extending between said flanges to be forced upwardly therein by impact against the ground, a torpedo 70 within the shell adapted to be driven rearwardly therefrom, and normally resting on said block, and means operated by upward movement of said nose-piece for expelling said torpedo rearwardly from said shell. 75

3. In an aerial grenade, the combination of an outer tubular sheet-metal shell, having stabilizer blades integral therewith, a breech-block secured within the lower end of the 80 same, having a recess in its upper part containing an expelling charge and a hollow portion, open at the bottom, in its lower part, a nose piece slidably mounted in said hollow portion, and protruding from the 85 forward end of the shell, a torpedo to the rear of said breech block, means for firing said expelling charge when said nose-piece is driven rearwardly, and means for firing the bursting charge in said torpedo after an 90 interval of time after the firing of said expelling charge.

4. In an aerial grenade, the combination of an outer tubular shell of sheet-metal having stabilizing blades stamped out from the 95 upper portion thereof to extend therefrom in the axial direction of the shell, a torpedo in said shell, and means for exploding said torpedo on impact.

5. An aerial grenade, which comprises in 100 combination:—a torpedo-carrying gun-shell, open and provided with stabilizers at its rear end, and open and provided with spreading flanges at its forward end,—a gun-breech-mechanism within the gun-shell,—a 105 firing mechanism forward of the gun-breech-mechanism and in the outer end of the gun-shell, and consisting of an outwardly protruding nose and a firing pin both within the gun-breech-mechanism,—a breakable connection between the firing mechanism and the gun-breech-mechanism,—a torpedo within the shell detachably connected with the gun-breech-mechanism and containing a 110 charge of bursting explosive,—a firing fuse 115 within the gun-breech-mechanism which is exploded when the firing-mechanism encounters an exterior object and after the breakable connection is broken,—a primary delay fuse in the gun-breech-mechanism 120 which is exploded by the explosion of the firing fuse,—a bomb-expelling explosive charge within the gun-breech-mechanism and above the primary delay fuse, which is exploded by the explosion of the primary 125 delay fuse,—a secondary delay fuse at the forward end of the torpedo which is exploded by the explosion of the bomb-expelling explosive charge,—and a bursting explosive charge within the torpedo which is 130

exploded by the explosion of the secondary delay fuse.

6. An aerial grenade, which comprises in combination:—a torpedo-carrying gun-shell, open and provided with stabilizers at its rear end, and open and provided with spreading flanges at its forward end,—a gun-breech-mechanism within said shell embodying in successive order a firing fuse, a primary delay fuse, and a bomb-expelling charge,—a firing mechanism at the forward end of the shell which operates in connection with said gun-breech-mechanism after an encounter with an exterior object, to fire the firing fuse,—a torpedo within the gun-shell detachably connected with the gun-breech-mechanism and embodying in successive order a secondary delay fuse and a bursting explosive charge.

7. An aerial grenade, which comprises in combination:—a torpedo-carrying gun-shell, open and provided with stabilizers at its rear end, and open and provided with spreading flanges at its forward end,—a gun-breech-mechanism within said shell embodying in successive order a firing fuse, a primary delay fuse, and a bomb-expelling charge,—a firing mechanism at the forward end of the shell which operates in connection with said gun-breech-mechanism after an encounter with an exterior object to fire the firing fuse,—a breakable connection between the firing mechanism and the gun-breech-

mechanism,—a torpedo within the gun-shell detachably connected with the gun-breech- 35 mechanism and embodying in successive order a secondary delay fuse and a bursting explosive charge.

8. An aerial grenade, which comprises in combination:—a torpedo-carrying gun-shell, 40 open and provided with stabilizers at its rear end, and open and provided with spreading flanges at its forward end,—a gun-breech-mechanism within the gun-shell which embodies in successive order a firing fuse, a primary delay fuse and a bomb-expelling explosive charge,—a firing mechanism forward of the gun-breech-mechanism and in the outer end of the gun-shell, which consists of a conical outwardly protruding nose 50 having a firing pin at its upper inner end,—a breakable connection between the firing mechanism and the gun-breech-mechanism,—a torpedo within the shell detachably connected with the gun-breech-mechanism and embodying in successive order a secondary delay fuse and a bomb-expelling explosive charge.

In testimony whereof I have hereunto signed my name this fourteenth day of June, 60 1916.

LESTER P. BARLOW.
